UNITED STATES PATENT OFFICE.

WILLIAM B. COLLINS, OF BEN AVON BOROUGH, PENNSYLVANIA.

DISPENSING PACKET FOR WAXED PAPER.

Application filed November 20, 1922. Serial No. 602,114.

To all whom it may concern:

Be it known that I, WILLIAM B. COLLINS, a citizen of the United States, and residing in the borough of Ben Avon, in the county 5 of Allegheny and State of Pennsylvania, have invented or discovered the new, useful, and Improved Dispensing Packets for Waxed Paper, of which the following is a specification.

10 My invention consists of a new and improved dispensing packet of waxed paper.

Waxed paper is largely used by housewives for many purposes, such as wrapping food stuffs. At the present time such paper is sold in the form of flat sheets stacked or piled one on the other, and then rolled about a tube, and the result is that the sheets readily become soiled, wrinkled and torn, making their use inconvenient and unsatisfactory, and resulting in a relatively large percentage of waste.

The object which I have in view is the provision of a dispensing packet of waxed paper which will preserve the sheets in perfect and sanitary condition until used, and from which the sheets may be removed one at a time without disturbing or in any way injuring the sheets remaining in the packet.

My improved packet is of the following 30 character.

A pile or stack of the waxed sheets is doubled or folded along its center line, and then inserted into a long narrow envelope having an open end preferably provided 35 with a flap. A length of wire or cord, preferably wire, is then inserted through holes in the closed end of the envelope and through the registering ends of the sheets, and the ends of said wire or cord are then 40 connected together to form a suspension loop, so that the envelope and its contents may be suspended from a nail or hook by means of said loop, with the open end of the envelope downward.

45 In the accompanying drawings Fig. 1 is a view in perspective showing my packet suspended from a nail, with the bottom end of the envelope open, and a human hand withdrawing a sheet of waxed paper from the bottom of the envelope; Fig. 2 is an 50 isometric view of the envelope with the flap of the open end turned in to close the envelope, and Fig. 3 is a broken plan view of a sheet removed from the packet.

55 The following is a description of the drawings.

A represents an envelope, of long and narrow shape, and made of a relatively thin and flexible paper. One end, the upper end in the drawings, of the envelope is closed, 60 while the other end is open and provided with a flap 1 which may be turned up into the envelope to close the same. B represents a plurality of sheets of waxed paper laid in a pile or stack, and then doubled or 65 folded once upon itself. The folded pile of paper sheets is then inserted into the envelope until the inner ends of said sheets substantially abut against the closed end of the envelope. A length of wire or cord, 70 preferably wire, C, is inserted through holes 2 in the closed end of the envelope A and in the adjacent ends of the sheets B, and the ends of the wire or cord are then connected together by twisting or knotting to 75 form a loop by which the packet is suspended as shown in Fig. 1. The flap 1 may now be pulled down and out as it does not function to support the sheets in the envelope. When the consumer desires to use 80 a sheet of the waxed paper, the hand is inserted into the lower portion of the envelope and the outermost sheet, indicated at B' in Fig. 1, is grasped and given a downward pull which tears the hole through to 85 the top of the sheet as indicated at 2^a in Fig. 3, thus releasing the sheet and allowing it to be pulled down out of the envelope without disturbing the remaining sheets.

The sheets may thus be removed one by 90 one, or two or more at a time, until the entire supply of sheets is exhausted, and the sheet last removed will be found to be as smooth, unwrinkled and unsoiled as were 95 all the others.

It is evident from the foregoing that my improved packet provides a most convenient and attractive method of putting up waxed paper for the market. It is also evident that the packet may be hung up on the wall 100 of a kitchen, where it will be ready for immediate use, and will be meantime out of the way.

What I desire to claim is:—

1. In a dispensing packet of sheets, the 105 combination of an envelope with an opening at one end, a pile of sheets, said pile folded transversely and inserted into said envelope with free edges of the pile adjacent the closed end of the envelope, and a 110 suspension loop for the packet extending through holes in the closed end of the en-

velope and through the corresponding portion of the sheets.

2. In a dispensing packet of sheets, the combination of an envelope with a flapped opening at one end, a pile of sheets, said pile folded transversely and inserted into said envelope with free edges of the pile adjacent the closed end of the envelope, and a suspension loop for the packet extending through holes in the closed end of the envelope and through the corresponding portion of the sheets, whereby the packet may be stored or transported with the flapped end of the envelope tucked in, and when hung up for use, the loop may be hooked over a nail or other support with the flapped

end of the envelope below and open for the downward withdrawal of individual sheets.

3. In a dispensing packet of waxed sheets, the combination of a relatively long and narrow envelope with an opening at one end, a pile of waxed sheets, said pile folded transversely and inserted into said envelope with free edges of the pile adjacent the closed end of the envelope, and a suspension loop for the packet extending through holes in the closed end of the envelope and through the corresponding portion of the waxed sheets.

Signed at Pittsburgh, Pa., this 13th day of Nov., 1922.

WILLIAM B. COLLINS.
